COMBINATION DIVIDER, INSIDE AND
OUTSIDE CALIPER

Erling M. Hellum, Duluth, Minn.

Application September 6, 1938, Serial No. 228,672

2 Claims. (Cl. 33—149)

This invention relates to combination tools and more particularly to a convertible and adjustable instrument to be used as a divider, or an inside and outside caliper.

The invention has for its principal object to improve upon such combination instruments by simplifying the structure in general and providing a more practical means of attachment and adjustment for the different legs.

10 A further object is to minimize the number of separate leg elements necessary in the conversion of the tool for its different uses and at the same time provide for a wider range in the spread of the tool in use.

15 With the foregoing, and other objects and advantages to be attained, as will hereinafter more fully appear, the invention consists in the general assembly and in the particular parts and combinations and arrangements of parts as hereinafter described and set forth in the appended claims, reference being had to the accompanying drawings illustrating a practical adaptation of the invention and in which:

20 Figure 1 is a face elevation of the tool arranged as a divider;

25 Figure 2 is an edge elevation of the tool as arranged in Figure 1;

30 Figure 3 is a face elevation of the tool arranged as an inside caliper;

35 Figure 4 is an edge elevation of the tool as arranged in Figure 3;

40 Figure 5 is a face elevation of the tool arranged as an outside caliper;

45 Figure 6 is an edge elevation of the tool as arranged in Figure 5;

50 Figure 7 is a face view of a detached leg member that is used interchangeably in adapting the tool for use either as a divider or inside caliper; and

55 Figure 8 is a fragmentary section, on an enlarged scale, taken on or about the line 8—8 of Figure 5.

Referring now to the drawings, the tool there-in shown comprises a pair of main body bars 10 which are hinged together near their upper ends as at 11, said bars being cooperatively engaged above the axis of the hinge 11 by the end portions of a circular spring element 12 which is constantly under tension and exerting its force to spread the bars 10 apart. A suitable manipulating stem or handle member 13 is provided at the middle of the spring element.

The free end portions 14 of the bars 10 are turned outwardly at an inclination and said end portions are slotted, as at 15 (see Figure 4) to re-

ceive detachable and adjustable leg members as will presently more fully appear.

The slots 15 extend some distance in the bars 10 above the out-turned end portions 14, the inner ends of the slots terminating adjacent an adjusting screw 16 which is attached at one end to a swivel stud 17 on one of the bars 10 and extending therefrom through an apertured swivel stud 18 on the opposite bar 10, the outer end of the screw having a knob 19 thereon. Working on the screw 16 is a knurled nut 20 which abuts the swivel stud 18 so that by adjusting the nut on the screw the spread of the bars 10 may be varied at will, said bars being constantly under the action of the spring element 12, as hereinabove described, and it being only necessary to rotate the nut 20 and thereby move it inward or outward on the screw 16 to control the spread of the bars.

The slotted free end portions of the bars 10 are provided with screw threaded apertures 21 near the ends of the bars and also where the inclined portions 14 merge with the main body portions of the bars, that is to say, aligned apertures of the same size are provided at these points in the pair of branches produced by slotting the end portions of the bars. Each aligned pair of screw threaded apertures 21 receives a similar screw element 22 which is utilized not only as a clamping screw but also as a set screw, as will be later more fully described. Each screw element 22 is provided with a knurled manipulating head 23 and a portion of the screw next to the head 23 is reduced in diameter, as at 24, providing a neck portion without threads which is of a diameter equal to or less than that of the body of the screw less the depth of the threads.

Normally, outside caliper legs 25, having curved, tapering end portions 26 and apertured opposite end portions, are hingedly mounted on the endmost screw elements 22 in the slotted end portions 14 of the bars 10. In most instances in which the tool is converted for its respective uses, these leg members 25 are carried on the bars 10 at the same time with additional leg members 27 which are utilized in adapting the tool as a divider or inside caliper, said leg members 27 being each pointed at one end, as at 28, and formed with a curved lateral offset 29 at its opposite end. One of the leg members 27 is shown detached in Figure 7, while the manner of carrying a pair of said members on the bars 10 of the tool out of the way of the applied pair of outside caliper leg members 25 is shown in Figure 5, in which relation the legs 25 are clamped by the

lower screw element 22 while the adjacent end portions of the leg members 27 which are inserted in the slots 15 of the bars 10 are held by the clamping effect of both the outer and the inner screw elements 22. In this connection, it is obvious that either the pointed ends 28 or the rounded offset end portions 29 of said legs 27 may be inserted and secured in the slotted portions of the bars 10 with the same effect.

10 In the assembly illustrated in Figure 5, leg members 27 positioned as they are on the bars 10 do not interfere in any way with the use of the tool as an outside caliper, it being obvious that the bars 10 can be adjusted in any relatively 15 spread position by manipulating the nut 20 on the adjusting screw 16 while at the same time the leg members 25 may be swung to different positions about the axes of their respective supporting and clamping screws 22.

20 In the use of the tool as a divider, as shown in Figure 1, or an inside caliper, as shown in Figure 3, it is only necessary to loosen the four screw elements 22 and shift the leg members 27 to the positions shown in full lines in Figure 1 and Figure 3, with either the pointed ends 28 or the rounded offset ends 29, as the case may be, downward, and then swing the outside caliper legs 25 up to the position shown in full lines in Figure 1 and dotted lines in Figure 3, after 25 which the two lowermost screw elements 22 are again tightened with clamping effect, while the two upper screw elements are inserted in only one of the pair of aligned openings 21 with set-screw effect against the adjacent portions of the leg members 27 inserted in the slots 15. In the arrangement of the leg members 27 as shown in full lines in Figure 1 is the arrangement of the tool as a divider or as also shown in full lines in Figure 3 with the leg members 27 in an inside 30 caliper arrangement, the leg members 25 in the upper position shown offer no interference in the respective uses for which the tool has been converted. However, should occasion require an exceptionally wide spread of the leg members 27 in 35 use either as a divider or inside caliper, as illustrated in Figures 1 and 3, the outside caliper legs 25 are detached from the bars 10 by withdrawing the endmost pair of screw elements 22 and readjusting the leg members 27 by setting 40 them in longitudinal alignment with the inclined end portions 14 of the bars 10 as shown in dotted lines in Figures 1 and 3. In this connection it is noted that in Figure 1 said leg members 27 are extended longitudinally so as to increase the effective working length of the legs as well as increase the spread thereof, in which case, of course, only the endmost screw element 22 impinges each leg member 27 but the clamping effect upon the inner end portion of the leg member 45 within the slot 15 above the lower screw, which is functioning merely with a set screw effect, is had by utilizing the upper screw element as a clamping screw. It is further obvious that the leg members 27 need not, of necessity, 50 be set in direct longitudinal alignment with the end portions 14 of the bars 10 as shown in Figures 1 and 3, but they may be set either inwardly or outwardly out of exact longitudinal alignment therewith and yet the inner end portions of said 55 leg members may be readily secured in the slotted portion 15 by either clamping or set screw effect of the screw elements 22.

While the particular curved offset end portions 29 of the leg members 27 are primarily designed for the purpose of adapting the tool for use as an inside caliper, there may be some instances where said leg members may be applied 5 to the bars 10 to adapt the tool as an outside caliper by merely placing said leg members with said rounded off-set end portions 29 set inwardly toward each other.

From the foregoing it is apparent that a simple 10 and convenient combination tool is provided which is readily convertible for use as a divider or inside and outside caliper, at will, and in which the several leg members when not set for the particular use intended are conveniently carried on the tool out of the way of the leg members which are set for use.

While the structure illustrated in the drawings 15 illustrates a practical embodiment of the invention, it is obvious that considerable modification may be made therein without departing from the spirit of the invention as defined by the appended claims. The invention, therefore, is not limited to the specific construction and arrangement shown.

What is claimed is:

1. In a combination tool of the character described, a hinged pair of main supporting bars, each bar being slotted longitudinally at its free end portion to provide a bifurcation for the reception of interchangeable leg members, the opposed branches formed by the slotting of said supporting bars being provided with aligned pairs of screw threaded apertures for the reception of screw elements whereby to retain the end 35 portions of the leg members inserted between the branches, and screw elements selectively insertable one each in one of the apertures of the respective aligned pairs whereby to directly impinge the adjacent portion of the leg member inserted between the branches of the supporting bar with set screw effect, said screw element being alternatively inserted with threaded engagement in both apertures of the aligned pair whereby to clamp the branches of the supporting bar upon the inserted portion of the leg member.

2. The herein described tool, comprising a pair of main supporting bars pivotally joined adjacent one end and having their opposite end portions turned angularly away from each other and slotted longitudinally to provide bifurcations for the reception of detachable and interchangeable working leg members, the opposed branches of the bifurcation of each main supporting bar end portion being provided with aligned pairs of screw-threaded apertures, and screw elements insertable selectively and alternatively in either one or both of the apertures of each aligned pair thereof whereby to either pivotally support and clamp an apertured leg member in the bifurcation by insertion of a screw element in one aperture of an aligned pair and through the aperture of the leg member and into the other aperture of the pair, or to secure a leg member fitted slidably for its longitudinal adjustment in the bifurcation with either set screw effect against the leg member by the application of the screw element in one aperture of an aligned pair thereof or with clamping effect by insertion of the screw element in both apertures of an aligned pair at the side of the leg member.

ERLING M. HELLUM.
